UNITED STATES PATENT OFFICE.

FRANK E. WERNITZ, OF LEEDS, MISSOURI.

AUTOMATIC WINDOW-SHADE-ROLLER ADJUSTER.

Application filed May 10, 1922. Serial No. 559,949.

To all whom it may concern:

Be it known that I, FRANK E. WERNITZ, a citizen of the United States, residing at Leeds, in the county of Jackson and State 5 of Missouri, have invented certain new and useful Improvements in Automatic Window-Shade-Roller Adjusters, of which the following is a specification.

My invention relates to window shade 10 roller adjusters, and one object of the invention is to provide a device of this character which can be manufactured and installed at small cost.

A further object is to provide a device by 15 means of which the shade roller may be raised or lowered to let in more or less light and air above the shade, and which will lock the roller automatically in any of its adjusted positions.

20 In the accompanying drawing:

Fig. 1 is a fragmentary elevation of a window frame with my device installed thereon.

Fig. 2 is a side elevation of clamping 25 means for gripping the cord whereby the shade roller and its support are adjusted up and down.

Fig. 3 is a view similar to Fig. 2, with the 30 parts in position for releasing the adjusting cord.

Fig. 4 is a perspective view of a bracket forming one member of the clamping means.

Fig. 5 is a perspective view of a bell-crank forming the other member of the clamping 35 means.

Fig. 6 is a perspective view of one of a pair of shade roller hangers used in carrying out the invention.

In carrying out the invention I provide 40 cord clamping means embodying a bracket 2 having a pair of oppositely disposed arms 4, provided with holes 6 at their outer terminals. An eye 8 is formed in the upper forwardly curved end of the bracket 2 for a purpose which will hereinafter appear. Said bracket 2 is secured to the top cross member of a window casing A by a screw or the like (not shown) passing through hole 10 in the back of the bracket and 45 threaded into the window casing.

12 designates a bell-crank having trunnions 14 pivotally mounted in the holes 6 of the bracket 2. Said bell-crank 12 is provided on its lower arm with an upturned 50 terminal 15 having an eye 16 through which an adjusting cord 18 passes for the purpose

of operating the device. The upper arm of the bell-crank 12 has a pair of oppositely disposed tapered slots 20 through which the cord 18 passes.

20^a designates a retractile spring secured at one end to the bracket 2 and at its opposite end to the bell-crank 12 to hold the clamping means in active position.

22 designates a pair of rightangular shade 65 roller hangers having their terminals 24 and 26 bent at acute angles, and their intermediate portions formed into eyes 28 and 30 to provide bearings for the shade roller B, as shown by Fig. 1. Said hangers 22 are supported by the cord 18, which in turn 70 is supported by guides 31 secured to the top of the window frame A. The lower terminals of the brackets 22 are held from spreading apart and allowing the roller B to fall, 75 by a transverse cord 32, the ends of which are forced into the acute angles 24 and are held thereby from withdrawal, further security being had by knotting the ends 33 of said cord 32.

In practice the device is installed by securing the bracket 2 to the upper member of the window frame A. The guides 31 are then secured to the window frame near its upper corners and the adjusting cord 18 is 80 formed into a loop and run through said guides 31. Both ends of the cord 18 are then run through the eye 8 in the bracket 2, the slots 20 in the bell-crank 12, and the eye 16 in the terminal 15 of said bell-crank, 85 after which the ends of said cord 18 are knotted to prevent accidental withdrawal through the eye 16. The looped upper part of the cord 18 is then pulled down a suitable distance and secured in the acute angles 90 formed by the terminals 26 of the shade roller hangers 22. The curtain pole B is next placed in position in the hangers 22.

Normally the cord 18 is held stationary 100 by engaging in the narrow upper ends of the slots 20, but when it is desired to raise or lower the shade roller B the cord 18 is pulled down until it rocks the bell-crank 12 from the position disclosed by Fig. 2 to that disclosed by Fig. 3. This operation pulls 105 the cord 18 into the wider portions of the slots 20 so that the cord may be readily raised or lowered to any desired extent. After the shade roller B has been adjusted to the desired height the ends of the cord 18 are released, whereupon the spring 20^a 110 instantly restores the bell-crank lever 12 to

the position disclosed by Fig. 2, which operation again forces the cord 18 into the narrow portions of the slots 20, thereby securely holding the cord until it is again 5 manually operated.

From the foregoing description it is apparent that I have provided a device embodying the advantages above pointed out, and while I have shown and described the 10 preferred form of the invention I reserve the right to such modifications thereof as properly fall within the spirit and scope of the invention as claimed.

I claim:

- 15 1. A device of the character described consisting of a pair of shade roller hangers bent at right angles and having their terminals bent at acute angles, a transverse cord adjustably secured to the lower angular 20 portions of said hangers to prevent the same from spreading apart, another cord whose transverse intermediate portion is adjustably secured in the upper angular portions of the hangers, guides adapted to 25 be secured to a window frame and through which opposite portions of the last-mentioned cord freely run, and means adapted to be secured to the window frame for holding said last-mentioned cord in any of its 30 adjusted positions.
2. In a device of the character described, a bracket adapted to be fixed to a window frame and provided at its upper portion with an eye through which a cord freely 35 runs, a bell-crank fulcrumed to said bracket and having an eye in its lower arm through which the cord freely runs and a tapered slot in its upper arm for holding the cord at any point of its adjustment, means for 40 yieldably holding said bell-crank in position to hold the cord stationary until the same

is pulled downwardly to lower the bell-crank, and shade roller supports to which the cord is attached so that said supports may be raised or lowered by operating the 45 cord accordingly.

3. In a device of the character described, a bracket adapted to be fixed to a window frame and provided with an eye through which opposite portions of a cord freely run, a bell-crank fulcrumed to said bracket and having an eye in one arm through which the opposite portions of the cord freely run and two tapered slots in its other 55 arm for holding the opposite portions of the cords stationary until said bell-crank is actuated by pulling on the cord, spring- 60 means for normally holding the bell-crank in position to hold the cord stationary, and shade roller supporting means controlled by the cord so that the shade may be raised or lowered.

4. In a device of the character described, a bracket adapted to be fixed to a window frame and having an upper forwardly projecting portion with an eye through which a cord freely runs, a bell-crank fulcrumed to said bracket and having an eye in its lower arm through which the cord freely 65 runs and a tapered slot in its upper arm for 70 coacting with the latter and the forwardly projecting portion of the bracket in holding the cord at any point of its adjustment, means for yieldably holding said bell-crank in position to hold the cord stationary until the same is pulled downwardly to lower the bell-crank, and curtain roller supports to 75 which the cord is attached so that said supports may be raised or lowered by operating the cord accordingly.

FRANK E. WERNTZ.
